UNITED STATES PATENT OFFICE

173,325

PNEUMATIC TOOL FOR CUTTING SHEET METAL OR THE LIKE

Robert C. Quackenbush, San Fernando, Calif.,
assignor to A. B. Quackenbush Company, Glen-
dale, Calif., a copartnership

Application August 10, 1953, Serial No. 26,365

Term of patent 14 years

(Cl. D54—14)

To all whom it may concern:

Be it known that I, Robert C. Quackenbush, a citizen of the United States, residing in San Fernando, county of Los Angeles, State of California, have invented a new, original, and ornamental Design for a Pneumatic Tool for Cutting Sheet Metal or the like, of which the following is a specification, reference being had to the accompanying drawing, forming part thereof, in which:

Fig. 1 is a front end elevational view of a pneumatic tool for cutting sheet metal or the like showing my new design;

Fig. 2 is a top plan view;

Fig. 3 is a bottom plan view;

Fig. 4 is a side elevational view;

Fig. 5 is a rear end elevational view; and

Fig. 6 is a sectional view taken on the line

6—6 of Fig. 3 looking in the direction of the arrows but with the trigger omitted for convenience of illustration.

I claim:

The ornamental design for a pneumatic tool for cutting sheet metal or the like, substantially as shown.
